UNITED STATES PATENT OFFICE.

LEONARD CLAYTON RIDGE, OF TORONTO, ONTARIO, CANADA.

FILING APPARATUS.

Application filed April 19, 1922. Serial No. 555,623.

To all whom it may concern:

Be it known that I, LEONARD CLAYTON RIDGE, a subject of the King of Great Britain, and resident of 1411 Royal Bank Building, city of Toronto, county of York, Province of Ontario, in the Dominion of Canada, have invented certain new and useful Improvements in Filing Apparatus, of which the following is a specification.

10 The invention relates to improvements in filing apparatus as described in the present specification and illustrated in the accompanying drawings that form a part of the same.

15 The invention consists essentially of the novel construction of the folders and the means for slidably supporting same.

The objects of the invention are to facilitate the filing of documents, to provide a 20 form of folder in which the contents may be perused without the necessity of removing same, to provide a form of folder support which may be adapted to any form of cabinet and generally to provide a form of 25 filing apparatus which will be inexpensive of construction and efficient in operation.

In the drawings Figure 1 is a perspective view of a drawer of a cabinet, equipped according to the present invention, portions 30 of the walls being broken away to disclose the interior.

Figure 2 is a perspective view showing a folder constructed from a single piece of flexible material.

35 Figure 3 is a perspective view of a portion of a cabinet showing a modified form of trackway, or support for one end of a folder support.

Figure 4 is a perspective view showing 40 the manner of securing the trackways to the cabinet where the edge of the cabinet is curled.

Figure 5 is a perspective view showing 45 the end of a trackway secured to a drawer having a wall of a type different from those shown in Figures 1, 3 and 4.

Like numerals of reference indicate corresponding parts in the various figures.

Referring to the drawings A is a drawer 50 of conventional form, comprising a bottom 1, end walls 2 and 3 and side walls 4.

55 5 are longitudinally arranged trackways adapted to be supported in parallel arrangement on opposite sides of the cabinet A and consisting of metal rods having their straight ends 6 embedded in the end wall 3

directly above the side walls 4 and spaced sufficiently therefrom to permit of the folder supports sliding freely thereon, and having comparatively short right angle ends or legs 60 7 turned downwardly and embedded in the top edge of the drawer.

8 are bars adapted for transverse arrangement in relation to the drawer and having reduced ends 9 bent to the form of substantially closed eyes engaging the opposing trackways 5 and permitting of said bars sliding longitudinally of the drawer thereon.

10 are cords or strips of flexible material, of which there may be any desired number, 70 connecting adjacent bars 8 at intervals throughout the length of said bars and forming loop members 11 adapted for the reception of documents. If desirable each pair of adjacent bars 8 may be connected by individual cords 10, or as shown in the drawings a plurality of cords may be used, each connected at its ends to the endmost bars and simply looping around the intermediate bars.

15 In Figure 2 of the drawings the document or folder supports are shown as consisting of a single piece 12 of flexible material secured to each individual bar 8 so as to form loop members 13.

When setting up the trackways 5 they may be installed in a true straight line or horizontal position as shown in Figure 1, or they may be bowed slightly if desirable by simply exerting slight inward pressure on the legs 90 7 and securing same to the cabinet in this condition.

20 In Figure 3 of the drawings the trackways are shown as having elongated legs 14 extending downwardly at each end of the drawer and projecting into or through openings in the bottom thereof, said trackways being held against inward movement by simply securing one or both of the end riders or bars 8 against movement longitudinally 100 of the cabinet, for which purpose clips 15 of any convenient type may be employed.

25 In Figure 4 the legs 14 are shown as bent or turned outwardly to position the trackway directly over the side wall 4.

30 In Figure 4 the side wall of the drawer is shown as being curled as at 16 while in Figure 5 said side wall is indented or bent forming laterally projecting walls 17, and in installing the trackways in drawers having 110 walls of this type it is simply necessary to provide the top and bottom walls of the

projecting portions with openings and insert the right-angle ends of the trackways.

In the operation of this invention access is had to the desired folder by simply spreading apart the adjacent bars which slide freely along the trackways on opposite sides of the drawer, which has the effect of opening the desired cradle or loop and bringing the contents clearly into view.

10 What I claim is:

1. In filing apparatus, a drawer having side walls and end walls, trackways supported above said side walls and spaced therefrom, bars arranged transversely of said drawer and having eye ends engaging opposing trackways and a plurality of flexible strips connecting said bars at intervals therealong and forming looped supports between adjacent bars.

20 2. In filing apparatus, a drawer having side and end walls, rods extending parallel with one another, and with said side walls and having their ends embedded in the walls of said drawer and forming trackways, bars connecting opposing trackways and slideable thereon, and flexible folders in the form of strings connecting said bars and forming loops between adjacent bars.

30 3. In filing apparatus, a cabinet having a bottom and side and end walls, trackways comprising rods embedded at one end in one of the said end walls above the respective side walls, and having their other ends turned at right angles and embedded in the

top edges of the side walls of said cabinet, folder supports slideable on said trackways, and flexible folders in the form of strings connecting said folder supports and forming loops between adjacent bars.

4. In filing apparatus, the combination in 40 a cabinet having a bottom and side and end walls, a plurality of substantially parallel rods rigidly supported in a horizontal plane above said side walls and embedded at opposite ends in said cabinet, a plurality of transversely arranged bars loosely connecting said bars and slideable thereon, and flexible folder supports in the form of strings connecting said bars and forming loops between adjacent bars.

5. In filing apparatus, a cabinet, parallel bars mounted above the side walls of said cabinet and having their ends embedded in said cabinet, transverse folder supports slideable on said bars and movable towards and away from one another, and a plurality of flexible members extending longitudinally of said cabinet in spaced parallel arrangement and secured to each of said folder supports and forming flexible cradles there- 60 between.

Signed at the city of Toronto, Ont., this 31st day of March, 1922.

LEONARD CLAYTON RIDGE.
